ELMER L. SMITH AND FREDERIC B. FULLER, OF SPRINGFIELD, MASSACHUSETTS, ASSIGNORS TO PACKAGE MACHINERY COMPANY, OF SPRINGFIELD, MASSACHUSETTS, A CORPORATION OF MASSACHUSETTS.

WRAPPING MACHINE.

Application filed October 9, 1920. Serial No. 415,822.

This invention relates to an improved wrapping machine which is designed to facilitate the usual wrapping operation as applied to machine-wrapped articles by simplifying the structure, and arranging the various elements in a compact and novel manner.

The illustrated embodiment of the invention is designed more particularly to wrap 10 cartons of the usual rectangular shape, and is an improvement upon the structure shown in Patent 1,196,094 for a carton wrapping machine granted to Hermann O. Fischer, August 29, 1916.

15 The present invention is designed to simplify and coordinate the operating mechanisms whereby the machine is rendered more efficient in operation to permit operation at a higher speed than has heretofore been deemed practicable in devices 20 of this character and at the same time provide means for readily adapting the machine for wrapping articles of varying size whereby the necessity of providing a plurality 25 of machines for wrapping articles of different size is obviated with a consequent saving of time and expense.

Other objects of the invention relate to improved mechanism for facilitating the 30 feeding of the cartons to the wrapping mechanism, novel means for transporting the carton and wrapper therefor through the machine properly coordinated and simplified to act efficiently upon cartons of different size and shape, and new and improved mechanism for properly positioning the cartons and wrappers therefor in superposed position preliminary to the wrapping 35 operation.

40 Further objects of the invention relate to an improved arrangement of mechanism for folding the wrapper about the carton and facilitating the movement of the carton during the wrapping operation, novel and efficient mechanism of simple construction 45 for furthering the wrapping operation and transporting the cartons during the wrapping operation together with new and useful operating means therefor and simple 50 and efficient means for adjusting the necessary mechanism to readily permit the machine to operate with equal facility and dispatch upon cartons of different size.

Other objects of the invention relate to new and improved means for facilitating 55 the transfer of cartons to the delivery chute, as well as a novel arrangement of mechanism for simplifying and synchronizing the paste applying mechanism and elevating means whereby the general operation of 60 the machine is improved and simplified.

Other objects of the invention relate to improved means and arrangement of parts for mounting certain of the mechanism to permit various mechanisms to be simultaneously adjusted to readily accommodate the machine to cartons of different size.

A further object of the invention is to provide a machine of this character which is of simple construction and efficient in 70 operation.

Other objects of the invention relate to details of construction and improved features of arrangement and operation of the parts will be more fully set forth in the following detailed description.

Referring to the drawings:

Fig. 1 is a side elevational view, partially in section, of the improved machine;

Fig. 2 is a top plan view of certain of 80 the operating mechanism, taken substantially along the line 2—2 of Fig. 1;

Fig. 3 is a transverse sectional view taken substantially along the line 3—3 of Fig. 2;

Fig. 4 is a transverse sectional view taken 85 substantially along the line 4—4 of Fig. 2;

Fig. 5 is an end elevational view of the machine, partially in section as indicated by the line 5—5 of Fig. 2;

Fig. 6 is a detail elevational view of the 90 transporter and the operating mechanism therefor;

Fig. 7 is a detail perspective view of a portion of one of the transporter arms;

Fig. 8 is a side elevational view of the 95 wrapper-gripping mechanism, showing the jaws in gripping position;

Fig. 9 is a side elevational view of the wrapper-gripping mechanism, showing the 100 jaws in released position;

Fig. 10 is a top plan view of the wrapper-gripping mechanism, showing the location of the actuating means therefor;

Fig. 11 is a perspective view of the holding mechanism for the carton and the wrapper therefor, illustrating the position of the 105

carton and wrapper prior to the commencement of the wrapping operation;

Fig. 12 is a perspective view of the mechanism for elevating the carton after the completion of the wrapping operation;

Fig. 13 is a transverse sectional view of the mechanism for applying paste to a part of the end portion of the wrapper; and

Fig. 14 is a perspective view of an end portion of the wrapper, showing the manner in which the paste is applied thereto;

Fig. 15 is a perspective view of the mechanism for folding a part of the end portions of the wrapper;

Fig. 16 is a perspective view of the mechanism illustrated in Fig. 15, illustrating the position of the same after the fold has been made and showing the mechanism for slitting the ends of the wrapper;

Fig. 17 is a perspective view of one end of the carton after the same has been operated upon by the mechanism illustrated in Figs. 15 and 16;

Fig. 18 is a perspective view of one end of the carton as shown in Fig. 17 after one of the side edges has been folded in;

Fig. 19 is a similar view after the remaining side edge has been folded in; and

Fig. 20 is a view of the same after the flap has been pressed down;

Fig. 21 is a perspective view of the carton after the same has been forced upwardly with the wrapper showing the position of the wrapper relative to the same; and

Fig. 22 is a perspective view of the carton after the wrapper has been placed there-around;

Fig. 23 is a detail sectional view illustrating the position of the transporter-operating mechanism relative to the supporting shaft; and

Fig. 24 is perspective view of the supply magazine detached; while

Fig. 25 is a diagrammatic view showing the positions taken by the cross heads controlling the operation of the transporting mechanism as said mechanism is moved rearwardly of the machine;

Fig. 26 is a top plan view of the transporters and the operating means therefor.

In the embodiment of the invention as illustrated herewith, 1 designates the frame portion of the machine, which may be constructed in any desired manner to properly

support the operating mechanism, the frame being preferably formed with a flat-top portion 2 for supporting a part of the mechanism. A main power shaft 3 extends transversely of the frame and is mounted

in suitable bearings carried thereby, the shaft being provided at one end thereof with fixed and loose pulleys 4 and 5, whereby the shaft may be driven from any suitable source of power, the opposite end of said shaft being provided with a hand wheel 6 to permit

the mechanism being turned by hand, as may be necessary in adjusting the parts or making repairs. A gear 7 is fixed to the shaft 3 and meshes with a gear 8 mounted upon a counter-shaft 9, whereby rotation may be transmitted to the counter-shaft and from the counter-shaft to a longitudinally-extending shaft 10 through suitable intermeshing bevel gears 11 and 12.

Mounted upon an eccentric carried by the shaft 10 is an eccentric strap 14 to which is pivotally connected at 15 a link 17 while an arm 18 formed integral with said strap projects outwardly from said eccentric. The link 17 has its opposite end pivotally connected to one end of a lever 19, as at 20, while the arm 18 is pivotally connected to a lever 22, as at 23. The levers 19 and 22 are pivotally mounted upon a bearing rod 24 supported by the frame and extend upwardly therefrom and operate the feeding mechanism for placing the cartons and the wrappers therefor in proper superposed position preparatory to wrapping the same, as hereinafter described. It will be noted that the levers 19 and 22 are rocked in opposite directions but are both operable directly from a single eccentric 14 thereby effecting a simplification in the operating parts of the machine.

The cartons to be wrapped and the wrappers therefor are fed into the machine transversely thereof and from opposite sides through mechanism actuated by the levers 19 and 22. A supply magazine 25 of the proper size for receiving the cartons, is located adjacent to one side of the machine and may be supported from any suitable portion of the frame. The supply magazine is provided with four side walls 25^a, 25^b, 25^c, and 25^d suitably positioned for the reception of square or rectangular cartons, two of the contiguous walls as 25^a and 25^b being extended upwardly a considerable distance above the walls 25^c and 25^d, the walls 25^c and 25^d being preferably each provided with an outturned lip 25^e to permit the more ready insertion of the cartons. This construction greatly facilitates the insertion of cartons in the machine since as the cartons are pressed against the upwardly extending sides 25^a and 25^b they automatically align themselves and tend to take up such positions as to permit them to readily fall into the supply magazine in proper position to be fed to the wrapping mechanism. The cartons to be wrapped, as indicated at A, are placed in the magazine 25 at a rate substantially equal to the speed of operation of the machine, whereby one, or more, of said cartons is constantly present at the bottom of the magazine. The bottom portion of the magazine 25 is open at the two opposite narrow sides, the wide side portions having inturned flanges 26

for supporting the articles and serving as tracks upon which the articles may slide,— (see Figs. 1 and 3).

A fixed bar 27 provided with oppositely-inclined beveled faces extends substantially across the machine and serves as a track for a pair of reciprocating carriers 28 and 29, which carriers are connected to the upper ends of the levers 19 and 22, respectively, by means of links 30 and 31. The carrier 29 is mounted to reciprocate beneath the magazine 25 and has pivoted thereto a catch 32 which is normally held in the position shown in Fig. 3 of the drawings by suitable mechanism such as a spring 33 and stop 34. It will be seen upon reference to Fig. 3 of the drawings that when the carrier 29 is moved to the right the catch 32 will engage the lowermost carton A and move the same to the right into position to be wrapped, while upon the return movement of the carrier 29 the catch will be depressed against the tension of the spring 33 by having its inclined upper surface engaged by the lowermost carton but, upon passing the magazine will be released and again assume the position shown in Fig. 3, preparatory to moving the next carton. This construction facilitates the operation of the machine since it permits a carton to drop to the lowermost portion of the magazine immediately after the preceding carton has commenced its movement towards the longitudinal center of the machine, and this insures that a carton be always in position to be moved towards the longitudinal center of the machine immediately upon the return of the carrier to the position shown in Fig. 3 of the drawings thus enabling the carrier to move more rapidly and the speed of the wrapping mechanism to be correspondingly increased. A pair of flanged guides 35 and 36 extend transversely across the machine from the lower flanged sides of the magazine and form a guideway for the package A as it is moved inwardly by the carrier as well as a support for the same after it has been properly positioned relative to the wrapper. (See Fig. 11.) A stop 25' disposed between the flanged guides serves as an abutment to position the articles accurately with respect to the wrapper when fed forward by the carrier 29.

U-shaped channels 37 and 38 extend transversely of the machine substantially parallel with and above the flanged guides 35 and 36 and at each side thereof, and are adapted to support the wrappers for the cartons in suitable position for applying the same. The wrappers B are fed into the channels 37, 38 by any suitable form of paper-feeding mechanism (not shown) and are deposited therein at a proper point to be engaged by the gripping mechanism supported by the carrier 28 and thereby successively brought into position to be applied to the cartons. The carrier 28 supports a gripping head 40, (see Figs. 8, 9 and 10) which carries the gripping mechanism and is movable transversely of the machine under the influence of the lever 19. It will be noted that the levers 19 and 22 are so connected with the eccentric strap that they are moved to draw the carrier for the carton 29 slightly in advance of the inward movement of the wrapper feed carrier 28 so that the succeeding upward movement of the carton toward the wrapper may be started while the wrapper is finishing its inward travel. In this way, the wrapper when it arrives adjacent the center of the machine does not need to wait for the upward movement of the carton which is effected as hereafter described.

Supported by the gripping head 40 is a fixed jaw 41 and a plurality of movable jaws 42 are pivoted to said head, as at 43, and are adapted to move towards and from said fixed jaw. Toggle links 44 and 45 pivoted together at 46 connect the movable jaws 42, with the main portion of the gripping head. A shoulder 46' on the head 40 serves as an abutment for the toggle links to prevent swinging of the same beyond the locking position for the jaws 42 as seen in Fig. 8. The pivot pin 46 of these toggle links is extended laterally of the gripping head as shown in Fig. 10 for a purpose which will now be described. A fixed bar 47 extends transversely of the machine adjacent the path of travel of the gripping head and this bar supports stops 48 and 49 properly positioned to engage the pin 46 at points at or near the limits of movement of the gripping head to actuate the toggle links and the movable jaws connected thereto, (see Fig. 2).

As the gripping head moves forwardly to engage the wrapper B (Fig. 8), the edge of the wrapper enters the open space between the jaws 41 and 42 which are presented to the paper in open position and at approximately the same time the pin 46 engages the stop 48 as shown in Fig. 10 of the drawings, thus causing the pin to move rearwardly and the movable jaws to swing up into position to grip the paper. In this position, the toggle links abutting against the shoulder 46' serve to lock the jaws 42 in their gripping position. As the gripping head is returned to its initial position by the carrier the wrapper is drawn along in the guides 37 and 38, and when the head reaches a point near the limit of its rearward movement and where it is desired to position the wrapper, the pin 46 strikes the stop 49, thus moving the links in the opposite direction and causing the movable jaws to drop into the position shown in Fig. 9 and release the wrapper.

Since machines of this character are designed to operate at a high rate of speed, the gripping head must reciprocate rapidly and difficulty might be encountered in having the wrapper jar out of position when released by the jaws. To prevent this movement of the wrapper after it is released and to insure that it be deposited at the same point each time in proper position for engagement by the carton to be wrapped, a dog 50 is provided which is pivotally secured to the gripping head, as at 51, and normally held by gravity in the position shown in Fig. 9. Upon reference to that figure, it will be seen that the dog is adapted to grip the edge of the paper slightly after the release of the movable jaws and thus prevent the paper from suddenly jarring out of position in which it is deposited on release of the movable jaws. In order that the dog will not interfere with entry of the edge of the wrapper between the fixed and movable jaws, a stop 52 is suitably positioned upon the bar 47 to be engaged by the dog as indicated in Fig. 9 of the drawings so that the portion designed to engage the wrapper is depressed to permit the edge of the wrapper to enter the space between the fixed and movable jaws. The jaws are arranged to open while the carrier is still moving and before it has completed its inward stroke whereby the jaws are carried out of engagement with the paper to leave the paper free to be wrapped about the carton. The paper is placed in proper registering position by striking a stop 50' suitably placed to engage the same while the dog 50 prevents the paper from rebounding after striking the stop and having itself only slight frictional contact with the paper wipes off the same during the completion of the movement of the carrier. The carton A to be wrapped and the wrapper B are thus brought into the machine by suitable mechanism from opposite sides thereof and placed in superposed position adjacent to the longitudinal center of the machine with the wrapper positioned directly above the carton and adapted to be engaged thereby when the article is forced upwardly by the mechanism about to be described.

As previously described, the mechanism for drawing the carton and wrapper towards the longitudinal center of the machine from opposite sides thereof is operated from the single eccentric strap 14 thus simplifying the mechanism and rendering more certain the proper synchronizing of the relative movements of carton and wrapper. The arrangement of the operating mechanism for feeding the cartons and wrappers inwardly towards the center of the machines is preferably such that the wrapper is deposited in position adjacent the longitudinal center of the machine slightly after the carton has been brought into position adjacent the longitudinal center of the machine thus resulting in the carton having started upon its upward movement slightly before or about the time that the wrapper reaches the limit of its inward movement. In this way more rapid operation of the parts can be had since there is no necessity for providing means for permitting lost motion.

Mounted for vertical movement in the machine is an elevator 54 normally positioned below the level of the lowermost carton A in the magazine 25 and which is supported by a vertically-slidable rod 55 mounted for movement in a bearing 56 carried by the frame of the machine. The means for raising and lowering the elevator at proper times comprises a lever 57 pivotally mounted upon the frame, as at 58, and adapted to be oscillated by a can 59 mounted upon the shaft 10 and having a suitable face groove engageable by the roller 60 carried by said lever. The lever has a forked end portion 61 engaging a roller 62 carried by the slidable rod, whereby the rod and the elevator carried thereby are raised and lowered upon oscillation of the lever. The period of movement of the elevator is so timed relative to the feeding mechanism for placing the carton and the wrapper therefor in superposed position in the machine that the elevator starts to rise shortly after the carton has been placed in position and engages the carton to raise the same to the upper position as shown in Fig. 1 of the drawings. A weighted block 64 carried by a stem 65 slidably mounted in a bearing 66 engages the upper surface of the wrapper above the carton shortly after the carton starts to move upwardly and prevents the wrapper from slipping relative to the carton. This block 64 is capable of free vertical movement for a certain distance whereby it occupies a position directly above and spaced slightly from the upper surface of the carton when the carton has been advanced to a point adjacent to the center of the machine and before it commences its upward movement.

As the carton and wrapper are carried upwardly by the elevator 54, the wrapper being forced upwardly by the movement of the carton, a curved plate 67 engages one side of the wrapper and smooths the same down over the side of the carton. In a similar manner the opposite side of the wrapper is engaged by a pivoted gate 68 which is spring-pressed against the carton by a coiled spring 92. The gate 68 engages the carton to be wrapped and thus the sides of the wrapper are folded smoothly against the sides of the carton and drawn closely over the top thereof, the carton and wrapper when in raised position presenting the appearance as shown in Fig. 21 of the drawings wherein the wrap-

per B is drawn over the top of the carton A and the sides *a* and *b* of the wrapper extend downwardly therefrom. A line of paste *c* is applied to one edge of the wrapper by any suitable means operable as the wrapper is brought into position adjacent the carton and a pivoted block 69 is located beneath and adjacent to this edge of the wrapper to prevent the pasted portion of the wrapper from 10 striking against other parts of the machine and depositing paste thereon. Two series of prongs 70 and 71 project upwardly from the block 69 and as the wrapper is pulled from the channel 38 it falls upon these prongs and 15 the line of paste is thus prevented from coming in contact with the mechanism. A coiled spring 72 tends to normally hold the block in the position shown in Fig. 1 of the drawings and to return the same to that position 20 if moved therefrom by engagement of the wrapper therewith. A hook 69' depending from the block 69 is adapted to be engaged by the undermost side of the elevator 54 during its downward movement and which 25 engagement swings the block 69 and prongs 70 and 71 downwardly for the purpose of removing the prongs from the path of a wrapper being fed into the machine.

When the carton and wrapper are positioned as shown in Fig. 21 of the drawings, other mechanism is brought into operation for completing the wrapping operation. A plate 73 slidably supported by a standard 74 is actuated at proper intervals by a lever 75 30 pivotally mounted, as at 76, and provided with a roller 77 mounted for actuation by a face cam 78. The plate 73 carries a horizontal folder 80 located adjacent to the edge *a* of the wrapper when the carton and wrapper 35 have taken the position shown in Fig. 21 of the drawings. Upon actuation of the plate 73 by the mechanism just described, the folder 80, which is provided with a slot 81 formed substantially centrally thereof for 40 the reception of the bracket 82, is slid forwardly and engages the edge of the wrapper to fold the same beneath the carton.

Prior to the forward movement of the folder 80, the elevator 54 is lowered out of 45 the path of the folder and during the start of the downward movement of the elevator the carton is supported above the path of the folder by the action of the gate 68 which 50 presses the carton against the bracket 82.

Immediately after the forward movement 55 of the folder 80 pushers 83 located above the folder and slidably mounted upon longitudinally-extending rods 84 are forced forwardly to engage the carton and wrapper and force 60 them bodily forwardly in the machine. The pushers 83 are actuated by an elbow lever 85 pivotally supported by the frame as at 86, and connected to the pushers by links 87. A link 88 connects one arm of the elbow lever 65 with a crank 89 carried by the shaft 9, where-

by the lever is actuated. The pushers 83 are spaced apart as at 90 (Fig. 11) to enable the same to pass the bracket 82, and upon forward movement of the pushers they engage the article and force the same forwardly 70 against the pivoted gate 68 which presses against the edge *b* of the wrapper and folds the same under the article so that the carton and wrapper then assume the form shown in Fig. 22 of the drawings, with the edges 75 *a* and *b* of the wrapper both folded under the article and in such a manner that the line of paste *c* carried by the edge *b* lies against the edge *a*, thus securing the wrapper in position. The provision of the curved 80 plate 67 makes it unnecessary to adjust the stroke of the pushers 83 so that when the carton is raised by the elevator 54 the forward edges of the pushers will engage the wrapper and wipe the flap *a* smoothly across 85 the side of the carton. In other words the pushers 83 may be retracted any distance from the carton as the latter is raised by the elevator and the curved plate 67 will serve to 90 press the flap *a* closely against the side of 95 the carton as the carton is raised into position to be engaged by the pushers. The pivoted gate 68, being spring pressed into engagement with the opposite side of the carton, exerts pressure thereon to hold the carton against the curved plate 67 with sufficient pressure to insure that the wrapper be drawn smoothly therearound.

The pivoted gate 68 is rotatably mounted on a shaft 91 and is pressed against the wrapper during forward movement of the carton by means of the coiled spring 92 which constantly tends to return the pivoted gate into horizontal position above the elevator 54, as at 68' (see Fig. 1). As the carton is pressed forwardly by the plungers, the pivoted gate is forced into a depression 93 whereupon the carton slides over the gate and upon a table 94 extending forwardly of the machine. The said table 94 is cut away 100 at the sides on its rear end so that it has a portion 94' which interfits with plates 152 105 of an elevator later to be described and as shown in Fig. 2. As the carton is forced forwardly upon the table, it slides under a 110 pair of pressure bars 95 and 96 arranged longitudinally of the machine.

In order to permit the machine to be used with cartons of different sizes without 115 making it necessary to use a separate machine for each size of carton, the magazine 25 can be readily removed from the machine and a magazine of different size substituted and at the same time guides 26 for the cartons and guides 37 and 38 for the wrappers 120 may be removed and replaced by guides of proper size for accommodating the cartons and wrappers with which the machine is to be used. In thus changing the mechanism to 125 permit its use with cartons of different size, 130

the rearwardly extending portion of the table 94 which carries the pivoted gate 68 is removed and a similar part also provided with a similar gate 68 substituted therefor 5 in order to space the pivoted gate a suitable distance from the curved plate 67 when used with cartons of different size.

To adjust the feed of the carton, the end stop 25' is relocated and the carrier 29 is re-10 placed with a similar carrier having a catch 32 properly positioned thereon to effect the feeding of the carton to the required location with respect to the elevator. To adjust the feed of the wrapper, the stop 50' 15 will be relocated in accordance with variations in the length of the wrapper to be employed. Obviously, however, if the change in size of the carton affects only its width, while its length remains the same, it will 20 not be necessary to make any readjustment of the carton feeding means nor of the wrapper feeding means.

After the plunger 83 has completed its forward movement, the carton occupies the 25 position indicated by C in Figs. 1 and 2 of the drawings and is then in position for continuing the wrapping operation by tucking and folding the end portions of the wrapper. Extending transversely of the machine sub-30 stantially beneath the carton when it assumes the position as indicated by C in Fig. 1 after having been forced forwardly by the plunger, is a cross-head 98 having a central depending post 99 slidably mounted in 35 guides 100 (see Fig. 4). A roller 101 carried by the arm 99 is engaged by the forked end 102 of a lever 103 pivotally mounted, as at 104 on the main frame 1 and provided with a roller 105 adapted to engage a cam groove 40 formed in one side of the cam 107, which is mounted on the shaft 10 whereby upon rotation of the cam the lever will be oscillated and the cross-head reciprocated in a vertical direction.

45 The cross-head 98 carries standards 108 and 109 located at opposite ends thereof, and each of these standards is provided upon opposite sides with vertical cutting blades 110 and offset creasing-blades 111. (See 50 Fig. 15.) The cutting blades 110 have inclined cutting edges 112 located at the upper ends thereof, and the creasing blades 111 are correspondingly provided with slightly curved upper edges 113. Cooperating with the creasing blades 111 are creasing bars 112' (Figs. 15 and 16) which are carried by the cutting blades 110 and normally engage the inner faces of said creasing blades. Each of the standards 108 and 55 109 is provided with a vertical channel 114 which serves as a guide for a post 115 slidably mounted therein, each post 115 being provided adjacent its upper end with an end tucker 116 comprising surfaces 116' 60 and 116'' at right angles to one another.

(See Fig. 16). Each post 115 is located between one pair of the oppositely-positioned sets of blades previously described and the tucker 116 carried by each post is preferably of such size as to nearly fill the space between 70 the opposite sets of blades. A coiled spring 117 connects each post 115 to its standard 108 which spring yieldingly carries each post with its respective standard so that the tucker is elevated slightly above the upper 75 edges of the two sets of blades. The raised position of each post 115 relative to its standard 108 is limited by a suitable stop piece 117'.

When the carton has been advanced to 80 a position directly above the standards 108, 109 as previously described, the continued movement of the mechanism raises the cross-head 98 and as the tuckers 116 are normally held in a position above the upper edges of 85 the adjacent blades, the tuckers first contact with the lower sides of the tubular extended end portions of the wrapper and tuck the same up against the end of the carton in advance of the upper edges of the blades. 90 When the tuckers 116 have moved upwardly to a point substantially on a level with the top surface of the carton, they are stopped by fixed overhanging plates 118 carried by longitudinally-extending guide rails 119, 95 whereupon on continued upward movement of the cross-head 98 the blades 110 and 111, advance beyond the tuckers 116, the resiliency of the springs 117 permitting and the parts occupy the position shown in Fig. 16 100 of the drawings. As the blades move upwardly past the tuckers 116, the lower edges of the sides of the wrapper slide between the blades 111 and the creasing bars 112' and a crease is formed in said wrapper sides 105 as indicated at d in the drawings. The continued upward movement of the blades 110 cause the cutting edges 112 to cut slits 110 through the extended portions of the wrapper, the cutting edges 112 being adapted to wipe past the edges of the plates 118 in order to prevent tearing of the wrapper and insure a proper cut in the same.

Immediately after the upward movement of the cross-head which brings the parts 115 into the position shown in Fig. 16 of the drawings, the cross-head with the mechanism carried thereby starts downwardly to its lower position the partially folded wrapper at this stage being shown at Fig. 17 of 120 the drawings wherein the unfolded portion of the wrapper comprises side flaps g and h and a top flap k. During the initial downward movement of the blades 110 and 111, the tuckers 116 remain stationary to hold the 125 tucked end of the wrapper in place and subsequently these tuckers 116 are moved away from the tucked end of the wrapper cover while folders carried by the transporter as 130 hereinafter described bend the cover flaps g

to the position shown in Fig. 18. In this manner the tucked end of the wrapper is held in place.

When the machine is used upon other sizes of cartons than that for which it is originally constructed the cross-head 98 and standards 108 and 109 together with the tucker heads 116 and tucking and folding blades associated therewith are removed and a similar structure, the parts of which have the proper proportions, is substituted therefor to insure the proper folding and slitting of the wrappers.

The transporter mechanism for carrying the partially wrapped cartons along the table for the further folding operation will now be described. In fixed position upon opposite sides of the machine are longitudinally-extending supporting frame members 120, each of which is provided with a longitudinally-extending slot 121 wherein is mounted for reciprocation a trunnion block 122. These members 120 are supported by a transverse bar 180 at their rear ends and are fixed in spaced relation upon the tie rod 181 at their forward ends. The tie rod 181 is supported by suitable brackets 183 which are spaced apart and secured to the bed 2 of the machine. A cross shaft 123 is rotatably mounted in said trunnion blocks and extends transversely of the machine. Adjustably fixed to the shaft 123 are transporter arms 124 each provided with corner folders 136 (see Fig. 7) and mounted at such points on the shaft 123 as to be adapted to properly engage opposite end portions of the partially wrapped carton as will be more fully described. The shaft 123 and the trunnion blocks by which it is supported in the slots are reciprocated by means of a link-rod 125 connecting the shaft 123 with the lever 85 in such a manner as to cause forward movement of the shaft to take place at approximately the same time as the advance of the plunger 83.

The transporter arms 124 serve to transport the cartons from the point where they are deposited by the plungers 83 which point is indicated by C in Fig. 1 of the drawings, to a point adjacent folding plates 140. It will be seen upon reference to Fig. 1 of the drawings that the plungers 83 are adapted to move the cartons from their positions upon the elevator to the point indicated by C in Fig. 1 of the drawings while the transporter arms 124 are given a somewhat shorter range of travel and successively move the carton from a point where they are deposited by the plungers 83 forwardly into position for the paste to be applied thereto. Thus, the transporter arms 124 must advance with each forward movement of the plungers 83 but are not required to move as great a distance. This relation permits the transporter arms 124 to be operated by the

lever 85 which operates the plungers 83, the rod 125 for operating the transporter arms being connected to the lever 85 nearer to its pivot point than are the plungers 83 since the transporter arms are to travel a shorter distance than the plungers.

The transporter arms 124 are double ended as shown and each end of each arm 124 is provided with corner folders 136 comprising angle plates with a portion 137 for engaging the end of the carton and portion 138 for folding the corner flap g of the wrapper (see Fig. 7).

In order to secure proper operation of the transporter arms and to suitably time the movement of the same, relative to the other parts of the mechanism, a pair of double ended cranks 126 and 127 are fixed to the shaft 123 one adjacent each end thereof for controlling the rotation of the shaft and the rotative movement of the transporter arms. (See Fig. 6.) The double crank 126 is located at the right end of shaft 123 looking forwardly of the machine and is provided with rolls 128 located at opposite ends thereof, and the double crank 127 is located at the left end of said shaft 123 and is provided with similar rolls 129. The double crank 126 is so positioned upon the shaft 123 that one of the rolls carried thereby will be in position to engage a slot 130 formed in a fixed boss 181 carried by the bar 120 which is at the right of the machine while the double crank 127 is located at such a point that the rolls 129 carried thereby are adapted to run in and out of a groove 132 formed in a lever arm 133 pivotally supported as at 134 by one of the brackets 183. The travel of double crank 127 is such that one or the other of its rolls 129 is constantly within said slot 132.

The lever 133 is pivoted to a fixed support as at 134 and has pivotally attached thereto as at 134' a two-part link 156 the parts of which are capable of slight longitudinal movement relative to each other. The link 156 is actuated by the cam 107 to reciprocate the same a sufficient degree to insure proper actuation of the lever 133.

When the lever 85 draws the link 125 and the shaft 123 rearwardly, the transporter starts to move rearwardly of the machine and the link 156 is drawn slowly downwardly thus drawing the lever 133 into its downwardly inclined position as indicated by the inclined dotted lines in Fig. 25 of the drawings. The rearward roll 129 being in the slot 132 is drawn downwardly with the lever and thus rotating the shaft 123 in a counter-clockwise direction as seen in Fig. 6. As the shaft 123 is rotated, the forward roll 129 which is outside the slot, as shown in Fig. 26 of the drawings, swings upwardly through an arc-shaped path as indicated by the arrows in Fig. 25. The

forward roll 128 is also swung upwardly through an arc-shaped path nearly paralleling the curved path traversed by the roll 129. As the shaft 123 is thus rotated, the rearward roll 128 is drawn downwardly into the intermediate position indicated in Fig. 25 of the drawings and wherein the cross-heads are shown as being substantially vertical. The slot 130 serves as a stop to hold the rearward roll 128 against further rearward movement and thus compel continued anti-clockwise rotation of the shaft 123 as it moves rearwardly.

As the shaft 123 continues its rearward movement the lever 133 is moved upwardly by the link 156 until it reaches its normal horizontal position when an adjustable stop 133' carried by the lever 133 abuts a shoulder 183' to prevent further upward movement of the lever 133, and insuring that the slot 132 will occupy a horizontal position as the shaft 123 is subsequently moved forwardly. The two-part link 156 is provided with a coiled compression spring 156' as shown in Fig. 6 which permits a slight overthrow of the cam 107 to hold the lever 133 in horizontal position for a suitable period, thus making it unnecessary to require such accurate machining of the cam as would otherwise be necessary and also permitting proper adjustment in the position of the lever 133 through the adjustable stop 133'. The lower portion of the link 156 may slide upwardly in the sleeve carried by the upper portion against the force exerted by the compression spring 156' during the overthrow of the cam 107, as will be seen upon inspection of Fig. 6 of the drawings.

Thus, when the transporter commences its forward movement, the lever 133 is in horizontal position and remains in that position to serve as a guiding and controlling means for the transporter until the transporter has reached the limit of its forward movement.

When the shaft 123 is located at the limit of its rearward movement, as when the plunger 83 begins its forward movement the transporter arms 124 are substantially vertical and the forward roll 129 is positioned within the slot 132 formed in the lever arm 133 which arm is at that time in such position that the slot 132 is substantially horizontal and parallel with the slot 121, wherein by upon slight forward movement of the shaft 123 the rearmost roll 129 also enters the slot 132 and any tendency of the shaft 123 to rotate is resisted by the double crank 127 and the lever arm 133.

As the shaft 123 moves rearwardly from its intermediate position as shown in Fig. 25 of the drawings, it will be rotated approximately 90 degrees in a counter-clockwise direction to bring the cross-heads into substantially horizontal position. As the

shaft is thus rotated the transporter arms 124 are rotated substantially 90 degrees and these arms thus assume a substantially vertical position as shown in Fig. 1 of the drawings. As the transporter arms are thus rotated the angular wrapper folding portion 138 of the plate 137 carried by each arm rotates into engagement with the flap *g* of each end of the wrapper closely adjacent to the end of the carton and folds the same closely against the end of the carton and into the position illustrated in Fig. 18 of the drawing. When the flap has thus been folded into place, the portion 137 of the plate 136 engages the carton and forces the same forwardly with the continued forward travel of the transporter arms. It is to be understood that one of these transporter arms is located at each end of the carton, whereby both ends of the wrapper are simultaneously folded and the carton moved forwardly uniformly at both ends. As the carton is thus moved forwardly, the flaps *h* are engaged by rearwardly projecting folding plates 140 (see Fig. 2) and folded in against the flaps *g* previously folded by the transporter arms.

The package then assumes the form shown in Fig. 19 of the drawings, wherein the flaps *g* and *h* have been folded in position and the portion *k* extends outwardly from each end of the package. As the transporter arms continue to advance the package along the table 94, it is brought into position D adjacent the folding plates 140 and the oppositely extending flaps *k* rest upon the uppermost edges 140' of the folding plates 140 while the package is held in position upon the table 94 by the pressure bars 95 and 96. The package remains in this D position until advanced to position E and is advanced to E position by the advance of a package being pushed along the bed by the transporter. When advancing from its D to E position the flaps *k* are drawn under corrugated plates 144 positioned above the paste receptacle while the package is held in position upon the table by the pressure of bars 95 and 96. (See Figs. 2, 5, 18.)

Shafts 145 and 146 are located upon opposite sides of the machine and mounted for oscillation in suitable bearings 147 and 148, respectively. Fixedly secured to one end of each shaft 145 and 146 are crank arms 149 and 150 positioned above the paste receptacles 142 and 143, respectively, and capable of being partially immersed in the paste contained therein upon suitable oscillation of said shafts. When the package is positioned at E and opposite the paste receptacles and at which time the flaps *k* project under the plates 144, the shafts are oscillated by means which will be more fully described hereinafter to raise the crank arms

149 and 150 and the bars 151 carried thereby to press the bars against the under surface of the flaps and apply lines of paste thereto. It will be understood that the bars 151 are so located as to register with the corrugations formed in the corrugated plate 144 when they are raised and thus prevent paste coming into contact with any part of the machine, or being deposited where it can come into contact with the outer surface of the package. The paste-applying mechanism is timed to operate when the package reaches the proper point in its travel and the package is forced forwardly from this point by the pressure imparted to successive packages as they are brought forwardly by the transporter arms. From this point the package is advanced as succeeding packages are brought into paste applying position until it is deposited upon an elevator 152 for completion of the folding operation.

Immediately after delivering the package to the position D, the transporting mechanism, which has reached the limit of its forward movement, starts to return to its initial position in the manner previously described.

When the package is being forced forwardly by succeeding packages, as previously described, the flaps *k*, to which paste has been applied, extend outwardly from opposite ends of the package beneath oppositely positioned rollers 160 located at opposite ends of the elevator. (See Fig. 5.) The elevator 152 is supported by a post 161 slidably mounted for vertical movement in a guide 163 carried by the frame and is actuated from the shaft 10 by mechanism which will now be described. A crank 164 carried by the shaft 10 has a crank-pin 165 movable in a slot 166 formed in one arm of an elbow-lever 185 which is pivotally mounted upon the frame, as at 167. The other arm of the elbow-lever has a forked end 168 engaging a roller 170 carried by the post 161, whereby upon rotation of the shaft 10 and post 161 and the elevator carried thereby are raised and lowered a distance equal to or somewhat greater than the thickness of the package. As the package is raised by the elevator, the rollers 160 press against the flaps *k* and force them closely against the ends of the package, thus binding all parts of the wrapper around the article and completely closing the package. As each succeeding package is raised by the elevator, the preceding packages are forced upwardly through a discharge chute 171 provided on opposite sides with a plurality of brushes 172 for engaging the ends of the packages and pressing the pasted flaps closely against the ends. As will be noted upon reference to Fig. 5 of the drawings, the brushes 172 are upwardly inclined and are sufficiently stiff to hold the packages against falling during the time in which the elevator is returning to its lowered position to receive another package.

The mechanism for oscillating the shafts 145 and 146 comprises cranks 145' and 146' journaled upon the ends of these shafts opposite the cranks 149 and 150. The cranks 145' and 146' are provided with rolls 174 and 175, respectively, which are positioned in a horizontal slot 176 provided in a plate 177 secured to the post 161 adjacent to the elevator 152 and movable vertically here-with under the influence of the elbow-lever 185. Cranks 145'' and 146'' are keyed or otherwise secured to the shafts 145 and 146 respectively and located adjacent to the cranks 145' and 146' to which they are respectively secured to provide means for oscillating the shafts 145 and 146 in a manner which will permit an adjustment of the degree of oscillation to be imparted to the shafts 145 and 146 and consequently an adjustment of the amount of throw to be imparted to the cranks 149 and 150. The means for adjustably securing the cranks 145'' and 146'' to the cranks 145' and 146' respectively is best illustrated in connection with the cranks 145' and 145'' in Fig. 5 of the drawings and as the means for connecting the cranks 146' and 146'' is the same in all respects only one of these connecting mechanisms will be described in detail. The crank 145'' as previously stated is keyed or otherwise secured to the shaft 145 and is provided adjacent its end with a pin 188 which is adapted to project through a slot 187 formed in the crank 145' and a nut 189 is adapted to be threaded upon the pin 188 to firmly clamp the crank 145'' to the crank 145'.

The pressure bars 95 and 96, paste receptacles 142 and 143, rolls 160 and separate sides of the discharge chute 171, are mounted upon two castings 190 and 191 respectively, located upon opposite sides of the machine and adjustably mounted upon a transverse bar 193. By means of this arrangement of the parts, the opposite pressure bars, paste receptacles, wiping rollers and sides of the delivery chute, may be adjusted towards or from the longitudinal center of the machine by adjusting the castings to different positions upon the bar 193. The slot 176 formed in the plate 177 permits the actuation of the cranks from the elevator in all positions of adjustment of the castings and the means for connecting the respective cranks 145' and 146' to the cranks 145'' and 146'' permits the parts to be so adjusted as to give the proper throw to the paste cranks 149 and 150 in any adjusted position of the castings. By thus providing means for adjusting the castings and the mechanisms carried thereby towards

and from each other this part of the wrapping mechanism can be readily adjusted to accommodate packages of different lengths and thus enable the machine to be easily 5 and quickly changed to wrap articles of different sizes.

After the machine is once placed in operation, a succession of articles continue to travel therethrough, and when one package 10 has been forced into position opposite the folding plates by the transporter arms, a previously folded carton is forced by it to a position opposite the paste applying receptacles and finally on to the elevator 152 and 15 against the stop 181 carried thereby in position to be raised by the next upward movement of the elevator. After the elevator has raised the article a sufficient distance and consequently forced a plurality of preceding articles upwardly, the elevator returns 20 to its initial position to receive the next article as forced from the table 94. The table 94 is provided with a portion 94' of reduced width which projects within a 25 slot 152' formed in the elevator 152 whereby when the elevator is drawn downwardly below the level of the table 94 the package supported by the extreme end of the table is prevented from following the elevator in 30 its movement below the table but is supported by the table in position to be engaged by the elevator in its upward travel and raised into engagement with the brushes carried by the discharge spout 171. This 35 construction also permits the operation of the elevator by a simple crank mechanism thus rendering unnecessary the use of complicated cams for retaining the elevator at the level of the table for a sufficient period 40 of time to permit the package to be deposited thereon. During the time when the elevator is moving upwardly the cranks 149 and 150 are actuated to apply paste to the flaps *k* of a succeeding package since at this time the 45 cartons are not being advanced by the transporters. The paste receptacles 142 and 143 are provided respectively with drain spouts 142' and 143' each of which is pivotally carried by its paste receptacle whereby the 50 drain spouts may each be rotated to a downwardly extending position as shown in dotted lines in Fig. 5 of the drawings whereby the paste may be entirely removed from each receptacle when the machine is not in use.

The various mechanisms engaging the carton and the wrapper therefor, are all capable of adjustment to permit the machine to operate upon articles of different size. The 60 pressure bars 95 and 96 are adjustable to accommodate articles of different thickness, while the transporter arms are adjustably mounted on the shaft 123 to properly operate upon articles of different length. The necessary adjustments for adapting the ma-

chine for use with articles of different size may be readily effected by manually shifting the adjustable parts, thus making it unnecessary to construct separate machines for use with articles of different size.

70

In the operation of the above-described mechanism the articles to be wrapped are constantly fed into the magazine 25 by any suitable means, whereby a constant supply of articles is maintained and rendered accessible to the carrier 29 for feeding to the wrapping mechanism. In a similar manner, any suitable form of sheet-feeding mechanism may be used for feeding wrappers into the guide channels 37 and 38 in position so that each succeeding wrapper may be engaged by the gripping head on each outward movement thereof. As the article to be wrapped and the wrapper therefor are placed in superposed position in the machine, the elevator 54 is actuated to force the article and wrapper upwardly to the level of the table 94 along which they are advanced and the wrapper folded around the article in the manner set forth. The transporter mechanism leaves each package at a point opposite the folding plates 140 and then begins its return movement during which the transporter arms are rotated at 180 degrees in order to bring the transporter arms behind the next package and force it forward in the same manner as in the previous operation. While the transporter arms are returning to engage the next succeeding package, the elevator 152 is actuated to raise the package placed thereon and returns to lowered position in time to receive another package as a package is again brought forward by the transporter arms.

105

110

115

While the various structural features employed have been particularly described in the embodiment of the invention shown herewith for the purpose of making the construction and operation of the mechanism clear to those skilled in the art, it is to be understood that certain changes may be made in the precise details of the construction shown without departing from the spirit of the invention, and that the invention is not to be limited to the details of construction as shown and described herein except as defined in the following claims.

115

What we claim is—

1. In a wrapping machine provided with mechanism for simultaneously wrapping articles and moving them in a direction longitudinally of the machine, means operable in opposite directions for advancing 120 separate articles to be wrapped and the wrappers therefor at different levels, stops for arresting the movements of the articles and the wrappers when they are relatively located in position to be engaged and operated upon by the wrapping mechanism, and 125

130

- means carried by the wrapper advancing means to prevent a rebounding movement of the wrapper when moved to position by the wrapper advancing means.
5. 2. In a wrapping machine provided with mechanism for simultaneously wrapping articles and moving them in a direction longitudinally of the machine, means operable in opposite directions for engaging and advancing a wrapper and for feeding separate articles to be wrapped at different levels, stops for arresting the movement of the article and wrapper when they are relatively located in position to be engaged and operated upon by the wrapping mechanism, common means for actuating said last named means, and means carried by the wrapper advancing means for frictionally engaging the wrapper for preventing a rebounding therefor when moved to position by the wrapper advancing means.
3. In a wrapping machine provided with mechanism for wrapping articles, means for feeding articles to be wrapped to the machine, a plunger and a wrapper-gripping device positioned at different levels and movable in opposite directions for transferring articles to be wrapped and the wrappers therefor into position to be operationally engaged by the wrapping mechanism, and means operable independently of the gripper for engaging the wrapper for preventing accidental movement of the wrapper after they have been transferred.
4. In a wrapping machine, means for placing a carton and wrapper therefor in superposed position, means for elevating said carton and wrapper, a pivoted gate normally occupying a horizontal position above the carton and wrapper to engage portions of the wrapper which cover the upper face of the carton, said gate being raised by the carton into position to press the wrapper closely against one side of the carton, additional means located above the elevating means to press the wrapper against the carton, and means for advancing the carton horizontally against the pressure exerted by said pivoted gate.
5. In a wrapping machine, means for placing a carton and wrapper therefor in superposed position, means for elevating said carton and wrapper, a spring pressed gate normally positioned to resiliently engage one side of the wrapper directly above the carton to press the wrapper closely against the upper face of the carton and adapted to press the wrapper subsequently against one side of the carton, a weighted member above the elevating means to press the wrapper against the upper side of the carton and means for advancing the carton horizontally against the pressure exerted by the spring pressed gate.
6. In a wrapping machine, means for placing a carton to be wrapped and a wrapper therefor in superposed relation, means for elevating the carton, means bearing on the upper side of said carton and wrapper for holding the wrapper in contact with the carton during the elevating movement thereof, a spring pressed gate constructed and arranged to successively engage the upper face and side of the carton as it is being elevated, and means for forcing the carton laterally against the spring pressed gate and thereby folding the wrapper therearound.
7. In a wrapping machine, means for placing a carton to be wrapped and a wrapper therefor in superposed position, means for folding the wrapper about the carton, means connecting the paste applying means and elevator whereby the former is operated simultaneously by and with the latter.
8. In a wrapping machine, means for placing a wrapper about a carton to be wrapped, and a reciprocating and rotating transporter operable to fold a part of the end portions of the wrapper and simultaneously force the carton forwardly through the machine.
9. In a wrapping machine, a table, means for placing a wrapper about a carton to be wrapped and for positioning the same upon the table, and a transporter having a combined reciprocating and rotating movement operable to fold a part of the end portions of the wrapper and force the carton forwardly along the table.
10. In a wrapping machine, a table, means for placing a wrapper about a carton to be wrapped and a double-ended reciprocating transporter non-rotatable in its forward movement and partially rotated in its reverse movement operable to fold a part of the end portions of the wrapper and move the carton forwardly along said table into position to be further acted upon by the operating mechanism of the machine.
11. In a wrapping machine, a table, means for placing a wrapper about a carton to be wrapped and positioning the same upon the table, cooperating means including a rotatable transporter for folding the end portions of the wrapper and forcing the same forwardly upon the table, and means for applying paste to a part of the end portions of the wrapper and folding the same into position upon the carton.
12. In a wrapping machine, means for drawing a carton and a wrapper therefor into said machine, means for placing the wrapper about the carton, means for advancing the carton longitudinally of the machine comprising a plurality of advancing mechanisms, and common means for operating said advancing mechanisms simultaneously through different lengths of stroke.
13. In a wrapping machine, means for

placing a wrapper around a carton, means for advancing the carton longitudinally of the machine comprising a plurality of rotating and reciprocating pushers, independent means for supporting and guiding said pushers, and common means for operating the same.

14. In a wrapping machine, means for placing a wrapper around a carton, means for advancing the carton longitudinally of the machine comprising a reciprocating pusher for moving the carton to a predetermined location, a reciprocating and rotating pusher for moving the carton from said location, a cam shaft, and common means actuated by said cam shaft for operating said pushers.

15. In a wrapping machine, means for placing a wrapper around a carton, means for advancing the carton longitudinally of the machine comprising a plurality of pushers having varying strokes, and common means for operating said pushers.

16. In a wrapping machine, a table upon which cartons are adapted to rest, means for applying paste to portions of the wrappers after other portions thereof have been previously applied to the cartons, means for elevating the cartons, said elevating means being movable both above and below said table, said table and elevator being provided with interfitting portions whereby the carton is supported by the table when the carton is moved below the table.

17. In a wrapping machine, separate paste applying means for applying paste to portions of wrappers after other portions thereof have been placed upon cartons, elevating means for elevating the cartons, and means operating in timed relation with said elevating means for actuating said paste applying means, said paste applying means being capable of adjustment towards and from each other without interfering with their operative connections.

18. In a wrapping machine, oppositely positioned paste applying means for applying paste to portions of wrappers after other portions thereof have been placed upon cartons, said paste applying means being capable of adjustment towards and from each other, elevating means for elevating the cartons, and common means for operating said paste applying means and said elevating means.

19. In a wrapping machine, separate paste applying mechanisms for applying paste to portions of wrappers carried by cartons, elevating means for elevating the cartons, and means including a channeled cross-head carried by the elevating means for actuating the paste applying mechanism.

20. In a wrapping machine, separate paste applying mechanisms for applying paste to portions of wrappers carried by cartons, ele-

vating means for elevating the cartons, means for actuating the paste applying mechanisms from the elevating means, and means for adjusting the stroke of the paste applying means.

70

21. In a wrapping machine, a feed table, means for successively positioning partially wrapped articles in line with the feed table, means for transferring the article to the feed table, a reciprocating transporter having a rectilinear forward movement operable to advance one article at a time across said feed table and being partially rotated in its reverse movement whereby it is enabled to pass idly above a succeeding article upon the feed table and to finally move into position behind said article so that it may advance the latter upon its next forward movement, and means for completing the wrapping operations while the articles are being advanced by said transporter.

75

22. In a wrapping machine, a feed table, means operating periodically to partially enclose an article within a wrapper and to position the partially wrapped article in line with the feed table, a reciprocable plunger to transfer the article onto the feed table, and a reciprocable and rotatable transporter adapted to be advanced to feed the article and its wrapper along the feed table and to be retracted and rotated to enable it to pass idly above another article subsequently positioned upon the feed table and into operative position behind said article so that it will advance the latter upon its next forward movement.

80

23. In a wrapping machine, a feed table, means operating periodically to partially enclose an article within a wrapper and to position the partially wrapped article upon the feed table, a transporter shaft, a transporter carried by said shaft, having oppositely disposed article engaging arms, means for reciprocating said shaft transversely to enable one of the transporter arms to advance an article along the feed table upon its forward stroke, and means for rotating said shaft during its retrograde movement to enable the transporter to pass idly over an article subsequently positioned upon the feed table and to bring the other of its arms into operative position behind said article so that it will advance the latter upon its succeeding forward movement.

85

24. In a wrapping machine, a feed table, means operating periodically to partially enclose an article within a wrapper and to position the partially wrapped article upon the feed table, a transporter shaft, a pair of transporter arms secured to said shaft and radiating in opposite directions therefrom, means for reciprocating said shaft transversely to enable one of said transporter arms to engage an article and advance it along the feed table upon the forward movement of

90

- said shaft, and means for imparting a half revolution to said shaft upon its return movement to enable both of said arms to pass idly above an article subsequently positioned upon the feed table and to bring the other of said arms into operative position behind said article so that it will advance the latter upon the succeeding forward movements of the shaft.
25. In a wrapping machine, means for placing a wrapper about a carton for a wrapping operation, and a transporter having oppositely disposed carton transporting and wrapper folding members adapted for a reciprocating and rotary motion arranged so that said members successively engage and act upon successive cartons.
26. In a wrapping machine, means for placing a wrapper about a carton for a wrapping operation, a transporter support carrying oppositely disposed carton transporting and wrapping folding members, the said support being arranged for a rotating and reciprocating movement whereby said members are operated to successively act upon successive cartons.
27. In a wrapping machine, means for placing a wrapper about a carton for a wrapping operation, a transporter for advancing a carton and wrapper for said wrapping operation having oppositely disposed wrapper folding and carton engaging members, means for reciprocating and rotating said transporter adapted and arranged so that the transporter is rotated when moving to carton engaging position whereby successive cartons are engaged by first one and then the other of said members.
28. A wrapping machine comprising in combination, means for supporting a plurality of articles to be wrapped in superimposed relation, a support for an article, means for transferring an endmost article therefrom onto said support, means for positioning a wrapper thereover, means for receiving said article and wrapper adapted to hold and initially fold said wrapper about the article, means for transferring said article from the support into said receiver, a table adjacent said receiver for supporting said article, a plunger for transferring said article and wrapper from said receiver to said table, means for forming certain subsequent folds in the wrapper as it rests upon said table, a transporter for moving said article and wrapper along said table and into a discharge chute, a discharge chute for receiving said article and wrapper, a member for feeding the same through said discharge chute, and means associated with said chute for completing the folding of the wrapper about the article as it is advanced therethrough.

In testimony whereof we have affixed our signatures.

ELMER L. SMITH.
FREDERIC B. FULLER.

- said shaft, and means for imparting a half revolution to said shaft upon its return movement to enable both of said arms to pass idly above an article subsequently positioned upon the feed table and to bring the other of said arms into operative position behind said article so that it will advance the latter upon the succeeding forward movements of the shaft.
- 6 25. In a wrapping machine, means for placing a wrapper about a carton for a wrapping operation, and a transporter having oppositely disposed carton transporting and wrapper folding members adapted for a reciprocating and rotary motion arranged so that said members successively engage and act upon successive cartons.
- 10 26. In a wrapping machine, means for placing a wrapper about a carton for a wrapping operation, a transporter support carrying oppositely disposed carton transporting and wrapping folding members, the said support being arranged for a rotating and reciprocating movement whereby said members are operated to successively act upon successive cartons.
- 15 27. In a wrapping machine, means for placing a wrapper about a carton for a wrapping operation, a transporter for advancing a carton and wrapper for said wrapping operation having oppositely disposed wrapper folding and carton engaging members, means for reciprocating and rotating said transporter adapted and arranged so that the trans-
- porter is rotated when moving to carton engaging position whereby successive cartons are engaged by first one and then the other of said members.
28. A wrapping machine comprising in combination, means for supporting a plurality of articles to be wrapped in superimposed relation, a support for an article, means for transferring an endmost article therefrom onto said support, means for positioning a wrapper thereover, means for receiving said article and wrapper adapted to hold and initially fold said wrapper about the article, means for transferring said article from the support into said receiver, a table adjacent said receiver for supporting said article, a plunger for transferring said article and wrapper from said receiver to said table, means for forming certain subsequent folds in the wrapper as it rests upon said table, a transporter for moving said article and wrapper along said table and into a discharge chute, a discharge chute for receiving said article and wrapper, a member for feeding the same through said discharge chute, and means associated with said chute for completing the folding of the wrapper about the article as it is advanced therethrough.
- 30 In testimony whereof we have affixed our signatures.

ELMER L. SMITH.
FREDERIC B. FULLER.

Certificate of Correction.

It is hereby certified that in Letters Patent No. 1,603,879, granted October 19, 1926, upon the application of Elmer L. Smith and Frederic B. Fuller, of Springfield, Massachusetts, for an improvement in "Wrapping Machines," errors appear in the printed specification requiring correction as follows: Page 4, line 85, for the word "can" read *cam*; page 9, line 94, for "145'", second occurrence, read *145"*; page 11, line 31, claim 3, after the word "means" insert the words *carried by the wrapper gripping device*, and line 81, claim 7, after the word "carton" insert the words *means for applying paste to certain of the end portions of the wrappers, means for elevating the wrapped carton*; and that the said Letters Patent should be read with these corrections therein that the same may conform to the record of the case in the Patent Office.

Signed and sealed this 16th day of November, A. D. 1926.

[SEAL.]

M. J. MOORE,
Acting Commissioner of Patents.
